E. B. REX

SCAFFOLDING BRACKET

Filed April 27, 1922

INVENTOR
EDSON B. REX

Edson B. Rex

UNITED STATES PATENT OFFICE.

EDSON B. REX, OF BUCYRUS, OHIO.

SCAFFOLDING BRACKET.

Application filed April 27, 1922. Serial No. 556,954.

To all whom it may concern:

Be it known that I, EDSON B. REX, a citizen of the United States, residing at Bucyrus, in the county of Crawford and State 5 of Ohio, have invented certain new and useful Improvements in Scaffolding Brackets, of which the following is a specification.

This invention relates to bracket devices for supporting builders' scaffolding or staging for use on buildings in the course of erection or being repaired, and has for one of its objects to provide a device of this character simple in construction, easily applied to and removed from buildings, inexpensive to manufacture, and which may be folded into relatively small space for shipment or storage.

With these and other objects in view the invention consists in certain novel features 20 of construction as hereinafter shown and described and then specifically pointed out in the claim, and in the drawings illustrative of the preferred embodiment of the invention:—

25 Figure 1 is a side elevation of the improved bracket.

Fig. 2 is a detail plan view of the support engaging jaw.

Two or more of the bracket devices are 30 employed, and spaced to correspond to the lengths of the staging planks, but one bracket only is shown for illustration.

The improved bracket device comprises a main horizontal supporting member or beam 35 B, preferably of a section of an L-bar having a head member A attached as by rivets at the inner end and with the other or outer end upturned as at I to form a stop to prevent the displacement of the platform or 40 planking of the staging or scaffolding which rests upon two or more of the brackets, as before stated.

The inner end of the head member A provides a clamping face having a spur K, and 45 projecting rearwardly from the inner end of the head member A is an angle shaped jaw member A', formed of a long and short arm and with the long arm integral with and offset with respect to the head member A. The short arm of the jaw member A' opposes and is spaced from the clamping 50 face of the head member A. The jaw member A' is adapted to overlap a stationary support, by way of example, one of the stud-

dings of the building being erected as illustrated in dotted lines at J. Operating through the short arm of the jaw member A' is a clamping screw G, having its outer end provided with a hinged turning handle H and its inner end formed with a swivelled head F, opposing the spurred clamping face of the head member A and formed with a plurality of spurs L.

By setting up the jaw member A' and head member A, in the manner as stated, the horizontal supporting member or beam B 60 may be firmly clamped to the studding J or other support as is obvious.

The head member A is formed with a depending ear M to which a link E is pivoted 70 at N, and pivoted at P to the free end of the link N is another link D, the latter having a lateral spur Q to be embedded in the supporting member J when the bracket is installed on the building.

Pivoted at one end at R, to the beam member B and at the other end at S to the link D, is a brace C.

When thus constructed and the parts arranged as in full lines in Fig. 1, and the jaw A' coupled to the member J at one point and the spur Q embedded in the member J at another point, a very strong and rigid bracket device is produced, which may be readily installed where required to support 80 a staging or scaffolding, and as readily disconnected and the parts C, D and E folded up against the beam portion B and its jaw portion A', as indicated by the dotted lines, which represents the device partly folded or 85 collapsed, for shipment or storage, or to facilitate the changing of the brackets from one part of a building to another.

The head member A and its jaw A' are of metal, preferably malleable iron or cast 90 steel, the beam member B and brace C of L metal, preferably steel, while the links E and D are of metal also preferably steel, all the parts being as light as possible consistent with the strains to which they are to be 100 subjected when in use.

The parts may be of any size or proportion and of any suitable material.

The preferred embodiment of the invention is disclosed in the drawings and set 105 forth in the specification, but it will be understood that modifications within the scope of the claimed invention may be made in the

construction without departing from the principle of the invention or sacrificing any of its advantages.

Having thus described the invention what is claimed as new is:

A bracket for the purpose set forth comprising a horizontally disposed supporting beam having an up-turned outer end, a rearwardly extending head member secured to the inner end of said beam and provided with a spurred clamping face and further with a depending ear at its inner end, an L-shaped jaw member integral with and projecting rearwardly from said head member and including a long and a short arm, a vertically disposed foldable supporting member formed of an upper and a lower section

pivottally connected together, said upper section having its upper end pivotally connected with said ear and said lower section having its lower end spurred, an inclined brace member having its upper end pivotally connected to said beam in proximity to the outer end of the latter and having its lower end pivotally connected to the lower end of said lower section, and a clamping screw threadably engaging with the short arm of the jaw member and provided with a spurred clamping head opposing said spurred clamping face.

In testimony whereof, I affix my signature hereto.

EDSON B. REX.
